UNITED STATES PATENT OFFICE

LEWIS M. HULL, OF BOONTON, NEW JERSEY, ASSIGNOR TO RADIO FREQUENCY LABORATORIES INCORPORATED, OF BOONTON, NEW JERSEY, A CORPORATION OF NEW JERSEY

ELECTRICAL AMPLIFIER CIRCUIT

Application filed July 14, 1927. Serial No. 205,783.

This invention relates to electrical amplifier circuits of the type employing vacuum tubes of the type having an electron-emitting cathode, an anode, and one or more additional elements or grids. It provides a balanced amplifier circuit for such vacuum tubes, whereby retroaction caused by coupling due to capacities between the vacuum tube elements and their associated connections, and especially retroaction caused by coupling due to the capacity between the control grid and the anode, is reduced or eliminated.

Advantageous features of my invention are that the tuning condensers may be directly connected to ground (i. e. to the framework, or low-potential portion of the system, which is normally grounded), thus producing structural simplicity of the amplifier, in practical embodiments thereof; that the A and B batteries may still be grounded as shown; that the compensating condenser, if used, may be connected directly between the control grid and ground or low-potential part of the system; and that simultaneously with the above arrangements the input to the stage may be connected directly between the cathode and the control grid of the vacuum tube.

Figure 1 shows my invention applied to a single amplifier stage. Figs. 2, 3 and 4 show variations of the arrangement of Fig. 1. Figs. 5 and 6 show cascaded amplifiers with arrangements similar to Figs. 1 and 2, respectively.

In Fig. 1, as shown, I employ a three-electrode vacuum tube of the ordinary kind, having anode P, cathode F, and control grid, G. The input to the amplifier stage, from whatever source or variety of circuit may be desired, is suitably connected directly between G and F. The cathode, or filament, F, may be heated from the direct current source A. In either, or preferably in each, of the connections from the cathode to this source, is included a coil. Coils in each connection are here shown at L₃ and L₄. The coil, or coils, are coupled to the plate coil L₂. If two coils are used, they should be so arranged as to have substantially equal mutual inductance with the coil L₂. They are preferably equal to each other as well, and the

inductance of each should ordinarily be substantially less than that of the plate coil L₂.

This may be accomplished by means of a twin winding, the parallel strands being laid or bonded together. For certain purposes it is desirable that the coils L₃ and L₄ (i. e. the twin winding) shall be coupled to the coil L₂ with a coefficient of coupling substantially equal to unity. In this case it is obvious that the inductance of coils L₃ and L₄ must be substantially less than that of the coil L₂, so that they will not prevent the plate current of the vacuum tube from transferring energy into the tuned circuit L₂—C₂. With a particular standard type of audion tube I have found that good results are obtained when the coil L₂ has 60 turns and the twin winding, which constitutes the coils L₃ and L₄, has 20 turns. These figures, however, are merely given by way of example, and the invention is not limited thereby.

The coils L₂, L₃ and L₄ should all be wound in the same sense. The coil L₂ may be tuned by means of the variable condenser C₂. The lower end of the coil L₂ is grounded through the batteries A and B, which may be bypassed by the condenser C¹. A compensating condenser, C₁, which improves the balancing action of the circuit, may be connected between the grid and ground, if desired, and I often find it advisable to do so.

A variation of this arrangement is shown in Figure 2, in which the tuning condenser C₂ is connected directly to ground, which is ordinarily the frame of the set as described above. The resonant circuit L₂—C₂ may be closed through the by-pass condenser C¹.

Another arrangement is shown in Fig. 3, in which the coil L₄ has the form of a radio frequency choke coil. It should have a high self-inductance in comparison with the coil L₃, and is not coupled to either L₂ or L₃. L₃, however, is coupled to L₂, as before, and may have substantially unity coupling therewith.

An arrangement including a double-grid vacuum tube is shown in Fig. 4. The circuit is similar to that of Fig. 2, but includes, in addition, the second grid, G₂, which may be connected to ground as regards alternating current, preferably by means of the by-pass

condenser C_1 . The grid G_2 may be given a positive direct current bias by means of a connection to a desired point in the "B" battery, or otherwise. Under certain circumstances, for instance if the tube elements have the proper geometrical arrangement, or the coils are properly proportioned, the circuit may be self-compensating, probably because of the natural capacity between grids G_1 and G_2 . This is shown by the dotted lines at C_1 . However, an external capacity may be used at C_1 if, for any reason, it is not desired to make use of the natural capacity alone.

Figure 5 shows a cascaded arrangement employing a circuit similar to that of Fig. 1, but in which the coil L_6 serves as the plate coil, for the purpose of coupling the tuned circuit L_2-C_2 to the anode-cathode circuit, instead of using the coil L_2 itself as a plate coil, as in the previous arrangements. An advantage of this arrangement is that the coupling ratio may be varied in order to fit the impedance of the tuned circuit L_2-C_2 to the impedance of the vacuum tube, whether the tube be of a single-grid or double-grid type. By making the impedance of the tuned circuit of substantially the same order as the tube impedance, greater efficiency and better operation is possible.

Figure 6 shows another cascaded arrangement, employing a circuit similar to that of Fig. 2, except that double-grid vacuum tubes are employed. Coupling between the stages is effected by means of coils L_5 coupled to the tuned plate coils L_2 .

From the foregoing specific examples, it will be seen that it is characteristic of my invention that I connect the input circuit of the amplifier stage directly between the control grid and the cathode of the vacuum tube, and that I may provide balancing capacity, if used, so as to be effectively between the control grid and ground, or between the control grid and a second grid in the case of a double-grid vacuum tube, said second grid being so related to ground as to cause capacity effectively between the control grid and ground. When either of these arrangements is employed, whether the vacuum tube is provided with one or more grids, it is covered by the expression "capacity effective between control grid and ground" or the like, as herein employed.

Any or all of these electrical amplifier stages are of course suitably used in radio receiving sets in combination with other radio or intermediate frequency amplifier stages, detectors, or audio frequency amplifiers. Certain combinations or variations of the circuits here shown, and modifications thereof, fall, of course, within my invention.

All degrees of coupling, whether unity coupling or substantially less than unity coupling, are comprehended by the term "coupled" or the like, as herein employed.

I claim:

1. An electrical amplifier stage comprising, in combination, a vacuum tube including an anode, a cathode, a control grid, and a second grid, input terminals for the amplifier stage constituted by said cathode and said control grid, a ground for said amplifier stage, a plate coil included in the circuit between said anode and said ground, a coil included in a connection between said cathode and said ground and coupled to said plate coil, and capacity effective between said two grids, whereby the elements of said amplifier stage may cooperate to reduce retroaction. 70 75

2. An electrical amplifier comprising, in combination, a vacuum tube including at least an anode, a cathode, and a control element; an input circuit for said amplifier connected between said cathode and said control element of said tube; an output circuit for said amplifier including a coil connected between said anode of said tube and ground; a coil connected between said cathode of said tube and ground and coupled to said coil in said output circuit; and balancing capacity 80 85 90 connected and effective between said control element of said tube and ground; said amplifier circuit being so proportioned and arranged as to be susceptible of balance to reduce retroaction between said input and output circuits thereof. 95

In testimony whereof, I affix my signature.
